UNITED STATES PATENT OFFICE.

WILLIAM F. OLIN, OF CHICAGO, ILLINOIS, ASSIGNOR TO WILLIAM DEERING & COMPANY, OF SAME PLACE.

GRAIN-BINDING HARVESTER.

SPECIFICATION forming part of Letters Patent No. 402,346, dated April 30, 1889.

Application filed August 20, 1884. Serial No. 141,088. (No model.)

To all whom it may concern:

Be it known that I, WILLIAM F. OLIN, residing at Chicago, in the county of Cook and State of Illinois, and a citizen of the United States, have invented certain new and useful Improvements in Grain-Binding Harvesters, of which the following is a full description, reference being had to the accompanying drawings, in which—

- 5 Figure 1 is a perspective view illustrating the devices pertaining to this invention; Fig. 2, a rear elevation; Fig. 3, a longitudinal section; Fig. 4, a top or plan view; Figs. 5 and 6, details of the sprocket-wheel and its supporting-bracket for driving the conveyer; Figs. 7 and 8, details showing one of the grain-carrying disks and its teeth; Fig. 9, a detail, being a perspective view of the sickle-pitman and clearing-tooth; Figs. 10 and 11, details showing the clutch; Figs. 12 and 13, details showing the devices for holding the stop-arm out of engagement; Fig. 14, a detail showing the connection of the pitman with the sickle.

My invention consists in the construction and combination of parts in a grain-binding harvester, as hereinafter specified in the claims annexed to this specification.

In the drawings a complete grain-binding harvester is not represented, but only so much of the frame-work as is necessary to illustrate the location and arrangement of the devices pertaining to this invention, and the parts not represented may be of the usual construction, arrangement, and operation of such omitted parts.

A represents the finger-beam or front sill of a harvester; A', the rear sill of the receiving-platform; A'', the sills which support the binder-frame, and A³ cross-sills supporting 40 the binder end of the front and rear sills and the sills on which the binder-frame is mounted; B, the upper arm or section of the gear-standard; B', the lower arm or section; and

B'' is a standard or post connecting the upper and lower arms. The upper and lower arms, as shown, are in the form of tubular sleeves to form bearings for the shaft which carries the main driving-wheel of the binding devices and the shaft which carries the binding-arm, as shown in Fig. 1, and, as shown,

this standard is bolted or otherwise secured to the front one of the sills, A'', by the bottom or foot B³; but the front sill, A'', could be dispensed with and the foot B³ be secured on top of the sill A. This foot or extension 55 B³ also furnishes a support and bearing for the crank-shaft, by which the packing-teeth are operated, and from this foot B³ projects upward a supporting piece or standard, B⁴, which is connected by an arm, B⁵, with the 60 post or standard B'', and furnishes a support for the butter, driving-shaft, and trip-clutch.

C is a compressor-finger, also forming the tripping-finger for throwing into operation the driving-gear which operates the binding 65 devices. This finger C is mounted on the end of a shaft, C', which has its bearings in a heel or extension, a, on the upright B'', and to this shaft C' is attached an arm or crank, C'', located on its opposite end outside of the post 70 or upright B'', which crank or arm C'', as well as the finger C, may be keyed or otherwise securely fastened to the rock-shaft C'. As shown, the end of the crank or arm C'' is provided with a hole to receive the lower end 75 of a connecting-rod, b, which passes through a cylinder or tube, c, in which is a central opening, c', which receives a coil-spring, c'', the upper end of which is in contact with an adjustable turn-buckle, b'', on the rod b. The 80 rod b is in two parts, one of which is passed through the cylinder c and receives the turn-buckle and collar b'' on its upper end above the cylinder, and carries a head, b³, on its lower end beneath the cylinder. The upper 85 part of the lower section of the rod b is hooked into the lower end of the head b³. The spring c'' encircles the connecting-rod b in the tube c, and one end of the spring rests on the bottom of the cylinder c, with its other end in 90 contact with the turn-buckle b''. This spring c'' is compressed as the finger C is turned down by the gavel compacted against it, and when the finger has acted and tripped the binder the spring will act and return the finger C to its stopping position. By using an adjustable set-nut or turn-buckle b' the proper adjustment of the connecting-rod can be made to suit the amount of movement required for compacting the gavel, and have the 100

spring act and return the finger after the trip has been made to operate, and it also enables the proper length of connecting-rod to be made to suit the required movement of the combined compressor and trip-finger, to cause such finger to act at the proper time for the different operations required of it.

D is a bell-crank lever, one arm of which, d , has thereon the casing or tube c , and the other arm, d' , of which carries a roller, d'' , as shown in Fig. 2. This bell-crank lever or arm D is pivoted to the standard or post B'' at the point d^3 , as shown in Fig. 3, so that it is free to vibrate on its pin or pivot and give a vibratory movement to the box or casing c , by means of which the connecting rod or pitman is forced or carried down, the crank or arm C'' throwing the compressor-finger back so as not to oppose the forward movement of the grain, leaving a clear space for the passage of the bundle from the binder.

E is the main gear-wheel for operating the binding devices, which wheel is mounted on the end of a shaft, E' , which runs or has its bearing in the sleeve B . The inner face of this wheel E, within its periphery, is provided with a cam-groove formed by an exterior wall, E'' , and an interior wall, E^3 , leaving between them a groove having a circular form, e , around the shaft E' as a center, with diagonal curved extensions e' on each side leading therefrom and connected by a semicircular groove, e'' , as shown in Figs. 1 and 3, and in this groove $e\ e'\ e''$ the roller d'' at the bend of the arms $d\ d'$ of the bell-crank D travels as the wheel E revolves, giving the bell-crank lever a vibratory movement, by means of which and the yielding or spring connection an elastic vibration is given to the finger C. This gear E, on its periphery, is also provided with a circular flange or track, E^4 , located just within the interior line of the cogs of the gear, which flange or track extends half-way, or nearly so, of the entire circumference of the gear, as shown in Figs. 1 and 3.

F is the driving-pinion for rotating the gear-wheel E, with the cogs of which the cogs of the pinion F mesh. This pinion is mounted on a shaft, F' , which shaft has its bearings in an arm or support, B^6 , extending up from the arm B^5 between the posts or uprights $B''\ B^4$. The pinion F is mounted on its shaft F' so as to be loose thereon; but the shaft has a continuous rotation from the pulley or wheel F'' , which is keyed or otherwise firmly secured to the end of the shaft and is driven by a belt or chain, as hereinafter described. As shown, the box or bearing for the shaft F' is on the arm B^6 , but it might be located in some other manner, so long as its position is such as to bring the wheels E and F into mesh. The inner face of the pinion has pivoted thereto by a suitable pin or pivot, f'' , a dog or catch, G' , one end of which has a heel or projection, f , and the other a stop or projection, f' , and, as shown, this dog or catch G' is held in its erect position by a spring, f^3 , one end of

which is secured to the dog or catch and the other to the face of the pinion in such manner as to have the spring act to throw the dog up when released from the clutch-tripping lever.

G is the driver keyed or otherwise firmly secured to the shaft F' , so as to rotate with the shaft. This driver is provided with rollers $g\ g$, and the path described by the rollers is such that they pass through the opening between the heel f and stop f' when the dog or catch G' is in its erect position, as shown in Fig. 2, so that the driver is free to rotate without engaging the dog or catch, but when the dog or catch is released and thrown down the heel or face f is raised sufficiently to be engaged by one of the rollers g of the driver G, and when so engaged the driver G and pinion F are locked together, driving the pinion as the shaft F' is rotated.

H is a clutch-tripping lever, arranged to have its acting end h' engage with the projection or stop f' , of the dog or catch G' and hold the dog or catch in its erect position, so as not to be engaged by rollers upon the driving-wheel, and the opposite end, h , of this lever H, as shown, is rounded and passes through the eye or loop b' on the end of the turn-buckle b'' , attached to the spring-rod b , which turn-buckle may be screw-threaded onto the rod so that it can be adjusted to give the proper pitch to the clutch-tripping lever to engage the dog or catch with greater or less force, to suit the desired size of the gavel.

I is a bracket or arm bolted or otherwise secured to the post or standard B'' , and having on its outer face a tubular bearing for the passage of a bolt or rivet, i' , by means of which a swinging arm or bracket, I' , is pivotally connected to the stationary arm or bracket I in such manner as to swing in or out, and to this arm or bracket I' , by a suitable pin or pivot, i^3 , is pivotally connected the locking-lever H. The arm h of the lever H engages at the rear of the pivot i^3 with the end i of the bracket I, forming a fulcrum or turning-point, by means of which, as the bracket or arm I' is swung forward, the acting end h' of the lever will be thrown out of position sidewise and held so as to be held out of line with the arm or bracket I' as it is thrown forward to carry the end of the locking-lever out of line of the dog or catch by the flange or track E^4 , on which an anti-friction roller, i'' , on the end of the arm or bracket I' travels as the wheel E is rotated, and, as shown, the arm or bracket is forced back after the roller i'' leaves the track E^4 by a spring-plunger; but some other means could be used for this purpose.

J is a spring-bolt or plunger, located in a tube or bearing, J' , on an arm, J'' , which arm J'' is attached by a bolt, j^3 , to the post or standard B'' , which bolt j^3 also serves to secure the bracket or arm I in position. The engaging end j of the bolt J is flattened, as shown, and enters a slot, j' , in the bearing J' ,

and the plunger is projected by a spring, j'' , located in the tube J' . When the locking-lever H is forced forward and out of engagement with the dog G' , the starting plunger or bolt is forced back, and as the arm I' is returned the spring j'' acts, when the roller i'' leaves the flange or track E^4 , to force the acting end h' of the locking-lever back into its normal position to engage the dog or catch G' . The locking-lever H prevents movement of the binder while the gavel is being accumulated and compressed, and when the compressor C is forced back by the accumulated grain sufficiently far to rock the shaft C' and throw down the crank C'' such movement will, through the rod b , draw down the end h of the locking-lever H , throwing up the engaging end h' of such lever, and releasing the dog or catch G' , which is then thrown forward by the action of the spring f^8 sufficiently to bring its heel f into position to be engaged by one of the rollers g of the driver G , making a connection between the driver G and the pinion F , by which rotation is imparted to the pinion, and through it to the gear-wheel E , to operate the binding devices. The wheel E makes one complete revolution to bind a bundle, and as this wheel is of greater diameter than its driving-pinion F some means must be provided to hold the locking-lever H and prevent it from engaging the dog or catch and stopping the movement of the binder before the binding operation is completed. The locking-lever H is held out of engagement through the swinging arm or bracket I' , to which it is pivoted, and the fulcrum formed by the end i of the bracket I in connection with the movements of the pivoted arm D . The finger C , when sufficient grain for a bundle has accumulated, as already described, trips the locking-lever, allowing the driver G to engage with the dog or catch G' , connecting the pinion F with the driving-shaft F' and rotating the wheel E , and as the wheel rotates the anti-friction roller d'' is acted on by the groove $e\ e'\ e''$, giving the pivoted lever D a vibratory movement as the roller passes into different channels of the groove. The roller, at the commencement of the movement is located at a point in the groove, as shown in Fig. 3, and first passes around in the circular portion e of the groove, thence into the radial curved portion e' , into the end portion, e'' , and thence into the side groove, e' , on the starting side, back to the starting-point, which line of travel gives the required movement to the arm or lever D for the operation of the compressor-finger C . The locking-lever H , after being tripped or released by the depression of the finger C , is carried forward by the roller i'' on the swinging arm or bracket I' , which passes onto the track or flange E^4 , throwing the bracket or arm I' forward and carrying the locking-lever to one side at its acting end h' , so as to clear the stop f' as the pinion F revolves, and after the roller i'' leaves the end of this flange E^4 the locking-lever has its forward end depressed by the position of the roller d'' in the cam-groove $e\ e'\ e''$, and as the wheel E completes its rotation the forward end, h' , of the locking-lever is returned, by the action of the rod b , spring c'' , and spring-plunger J , into position to engage the stop f' and raise the dog G' , unlocking the dog from the driver and allowing the driver and shaft to rotate without imparting rotation to the pinion F , which unlocking of the driver and the dog takes place as the roller d'' passes to the position shown in Fig. 3, stopping further movement of the binder. By this arrangement it will be seen that the compressor-finger forms a trip to release the locking-lever from the clutch-dog; that after the lever H is released its engaging end h' is thrown out of line of the clutch-dog by the action of the fulcrum and swinging lever I' through the engagement of the roller i'' with the track E^4 ; that as the roller leaves the track the end h' is returned to a position to engage the clutch-dog by the action of the plunger J ; that this acting end h' of the lever H is raised and lowered as the roller d'' travels in its cam-groove $e\ e'\ e''$ by the action of such cam-groove and roller and the spring c'' on the rod b , the result being that the dog and lever H are disengaged and engaged at the proper time to start and stop the binder.

K is a sprocket-wheel mounted upon a shaft, K' , which has its bearing in a swinging or pivoted frame or support attached to the bracing of the binder-frame, and between the sprocket-wheel K and its frame or support on the shaft K' is located a gear-wheel, K'' , which meshes with a gear-wheel, K^3 , on the end of a crank-shaft, K^4 . The frame or support for the shaft K' is pivoted or hung on the shaft K^4 , and the frame k is provided on each end k' with a slot, k'' , through which bolts k^3 pass for clamping the frame to the bracing K^5 . These slots k'' permit a swinging movement of the frame or support k , by which the wheel K can be made to act as a chain-tightener to take up any slack there may be in the driving-chain. The crank-shaft K^4 is made up of sections having crank-arms k^4 , arranged alternately on opposite sides of the shaft, as shown in Fig. 4, and this shaft is mounted in suitable bearings located on a bracing or support, K^5 , and arms K^6 , extending downward out from a front cross-bar, K^7 , which bar may be of the form of construction shown or otherwise. The bracing K^5 is bolted at its one end to the post B^4 , and its other end is turned down and bolted to the front sill, A or A'' . The front end of the cross-bar K^7 is bolted to the brace K^5 and its rear end is turned down and bolted to the rear sill, A' , in the form of construction shown.

L are disks, each having a diameter larger than that of the circle described by the cranks k^4 , and these disks are secured in any firm manner on the shaft K^4 to have a disk lie between two adjacent cranks, k^4 , with sufficient

space between the disk and the cranks for the location of the carrying-teeth L' , a tooth being provided for each side of each disk, and each tooth is pivoted between the disk and crank at the outer end of the crank by a suitable pin or pivot, l , which passes through the head of the tooth, and is secured in any suitable manner in the disk. Each tooth L' is provided on its heel portion with a tubular bearing, L'' , through which passes a rod, L^3 , one end of which is pivotally secured between ears l' on the under face of a cross timber or piece, L^4 , running from the front to the rear of the machine, and each rod L^3 is of sufficient length for the full stroke of the crank, so as to support the sliding bearing L'' during the entire revolution of the crank, and by means of this sliding socket L'' and the pivoted supporting-rod L^3 each tooth L' is maintained in a proper relation to enter and carry forward the grain, and is also held from flying out during the revolution of the crank.

M is a sprocket-wheel mounted on a shaft, M' , which shaft is supported in suitable bearings on the bottom B^3 of the binder-frame. The inner face of the wheel M is provided with an internal gear, m , which meshes with a pinion, m' , on the end of the shaft which carries the clearing-roller M'' , which roller is located at the delivery end of the platform-carrier, and furnishes the means for passing the grain from the carrier and for preventing it from passing around with the carrier.

N is a sprocket-wheel secured to the end of a crank-shaft, N' , which shaft, as shown, has one of its bearings in the bottom B^3 of the binder-frame, and its other bearings in a support extending up from the inner cross-piece, A^3 . This shaft N' is provided with two cranks, n , standing in opposite directions in relation to each other, and with a third crank, n' , for the attachment of the pitman-rod n'' , by means of which the sickle is driven, while the cranks n operate the packing-arms, so that this same shaft N' performs both offices of driving the sickle and operating the packing arms or teeth, thus dispensing with a separate shaft for operating the sickle, as has heretofore been practiced.

O represents the packing-fingers, two being provided in the form of construction shown; but more may be used, if desired, by adding additional cranks n to correspond with the number of fingers. Each packing-finger has its acting end formed into two fingers, o , as shown in Figs. 1 and 3, and the opposite end of the body of the finger has a rounded portion, o' , which passes through a guide, O' , on the frame-work of the machine to maintain the fingers in proper working relation.

P is the binding-arm formed of a single curved piece, as shown in Figs. 1 and 3, with an opening in its end, as usual, for the passage of the binding-cord. This arm is firmly attached at its heel or butt-end to a shaft, p , passing through the tubular arm B' , and is operated by a crank, p' , and a connecting-rod,

p'' , the upper end of which rod is connected to a wrist-pin on the wheel E , and its lower end is pivotally connected to the crank p' , crank which is firmly secured to the shaft p , so as to throw the arm up and down.

Q is a frame of a stirrup shape, having attached to its upper end a rod or link (not shown) through which and a suitable lever within reach of the driver (not shown) the frame Q can be slid back and forth on the shaft F' , on which shaft the frame is mounted, the shaft passing through an opening in the frame and an opening in the hub of the bevel gear-wheel r , located within the opening of the frame, which wheel meshes with a corresponding wheel, r' , as shown in Figs. 1 and 3. The wheel r' is secured on the end of a vertical shaft, r'' , which passes through the sleeve portion Q' of the frame Q and drives the roller or pulley R' , by means of which the adjusting-belt for the butts of the grain is driven. The bevel-wheel r' is keyed or otherwise secured to the shaft F' , so as to be revolved thereby, but free to move longitudinally thereon, by which means the bevel gear-wheels r and the frame Q can be moved fore and aft on the machine to bring the adjuster belt or canvas in proper relation for the length of grain.

R is the adjuster belt or canvas having slats on its exterior face, as shown, but which may be a plain canvas, if so desired. This canvas is supported on a suitable frame, one end of which comprises a roller, R'' , that is journaled in fixed bearings, so as to occupy a permanent position, and the opposite end carries the roller R' for driving the canvas, which roller is driven by the shaft r'' of the gear-wheel r' , so that the grain or receiving end of the adjuster belt or canvas remains stationary or fixed, while the delivery end can be changed to suit the length of grain.

S is the retainer, made of a piece of board or other suitable material and fixed to an arm, Q'' , projecting out from the sleeve Q' , which board or retainer is arranged in such relation to the inner end of the adjuster canvas or belt as to prevent endwise movement of the grain, which is liable to occur when the machine is tilted or inclined in order to lower the cut, by which means the tendency of the grain to move forward out of position is obviated, and the tendency of the adjuster to so move the grain by its constant movement is overcome, and it will be noticed that this board, being carried by the sleeve which carries the driving-shaft for the adjusting belt or canvas, maintains the same relation to the belt or canvas in whatever position the adjuster may be placed. As shown, the retainer is supported by a strap, s , bolted to the arm Q'' at one end and to the retainer on its rear face.

T is the driving-chain running around the wheels F'' , K , M , and N , for driving the respective shafts to which these wheels are attached, and imparting rotation to the binding

devices, the delivering and stripping roller, and the packing arms or fingers, which chain is driven from the main or drive wheel in any usual and well-known manner.

5 U is a finger projecting up from one end of a bar, U', in which is a longitudinal slot, U''. The slot U'' has located therein two half-boxes, t t', which receive the crank n' of the crank-shaft N', and make a connection between the 10 crank-shaft and the pitman-rod n'', which rod is screw-threaded, as shown, into the end of the finger U, so as to be in line with the body of the support U'. The outer face of the half-box t' receives the end of a set screw or bolt, 15 u, by means of which the half-boxes can be tightened and loosened to properly encircle the crank n', and, as shown, the bar U' is provided with a tube, u', in which is an opening leading to the half-boxes, by means of 20 which the parts can be properly lubricated, which tube is kept closed by a keeper, u'', which is held down by means of a spring, u', as shown in Fig. 9. This oil-box u' enables a 25 quantity of oil to be supplied, by which the parts will be kept lubricated for a considerable time, thus obviating the necessity of frequent oiling.

As shown, the support A'' for the inner 30 end of the bearing B' is in the form of an arched bar, the ends of which rest on the cross-pieces A³, as shown in Figs. 1 and 3, and the inner end of B' is provided with a forwardly-projecting foot, a', which can be bolted to the arched bar A'' and firmly support the 35 end of B', and this end of B' is provided with a rearwardly-projecting arm, a'', which supports and forms a bearing for the inner end of the rock-shaft C' of the trip and compressor-finger C. As shown, the cross-piece L⁴ is sup- 40 ported by a bar, L⁵, to the forward end of which the cross-piece is bolted, and the rear end of which is secured by suitable bolts to ears on the bearing B, the inner end of L⁵ forming a half-circle to properly encircle the 45 tube B.

The clearing-roller M'' is located to have its under face come slightly below the upper face of the platform-carrier, the result being that this roller forms a traveling stop, by which 50 the grain delivered by the platform-carrier will be acted on and, to a large extent, straightened before it passes onto the binding or receiving table, M⁸, and this straightening action is further facilitated by the incline M⁴, up which the grain must travel before passing onto the receiving-table, which incline is located in such relation to the carrying-fingers L' as to have such fingers act and assist in carrying the grain up the incline.

The cutting apparatus, reel, inner and outer divider, main or drive wheel, and other devices belonging to harvesting-machines are not represented, as they may be of any of the 65 usual and well-known forms of construction and arrangement. The delivery end of the platform-carrier is shown, and a small por-

tion of the sickle and its fingers, in order to show the relation of these parts to the delivery-roller and grain-delivering devices.

The operation of the devices pertaining to this invention is as follows: The grain as cut by the sickle falls upon the carrier-platform, and is carried by such platform to the delivery end thereof, and is passed from the delivery 75 end of the carrier-platform by the roller M'' onto the receiving end of the binding-platform M³, which platform is located above the packing-fingers, and in such relation thereto as to have their acting ends during their forward movement project through slots O'' in the platform, and engage and move the grain 80 forward against the compressor-finger, and this grain carried forward by the action of the fingers O is packed against the finger C, 85 and when a sufficient quantity of the grain is accumulated the pressure of the grain, as it is advanced by the packers O, carries the compressor-finger C back sufficiently far to rock the shaft C' and throw down the crank 90 C'', and through the connecting-rod b b' disengage the end of the stop arm or lever H from the dog or catch G', allowing the driver G to engage with the dog or catch and rotate the pinion F, which imparts rotation to 95 the wheel E and starts the binding devices. As the wheel E commences its rotation, the binding-arm is carried up, forcing the point thereof through the accumulated grain, and separating the grain for the bundle from the 100 inflowing grain, the binding-arm forming a stop for the inflowing grain. The binding-arm continues its advance movement until the gavel is encompassed by the binding-cord and the cord brought in proper position 105 for the tying devices on the end of the shaft E', which devices may be of any usual and well-known form to act and tie the knot and sever the cord. The encompassing of the bundle and the binding operation require 110 one complete revolution of the wheel E, and during this complete revolution the locking arm or lever H is held out of contact with the dog or catch G' by the swinging arm or hanger I', as already described. As the binding-arm commences its upward movement, the roller d'' engages with the circular portion e of its cam-groove, holding the finger C, in order that the grain for the bundle may be 115 compressed between it and the binding-arm, 120 which compression takes place while the binding-arm ascends. When the roller engages with the part e' of the groove, the finger is dropped to permit the discharge of the bound bundle, to be again raised as the roller on the 125 bell-crank engages the portion e³ of the cam-groove, and maintained in that position, at which time the locking arm or lever H is brought into position to engage the dog or catch G' and unlock the driver from the pinion F'' and stop further rotation of the wheel 130 E and further movement of the binding devices, at which time the binding-arm has returned to its normal position and the parts

are in the position shown in Fig. 3. The grain as it leaves the delivery end of the carrier-platform passes over the stripping and delivering roller M'' and is engaged by the teeth L' and carried forward to be operated on by the packing-fingers and forced by the action of these fingers against the compressor, and the fingers L' being arranged in pairs alternately on each side of their carrying-shaft, two or more fingers engage with the grain at the same time and carry it forward, and when one set of these fingers pass from the grain the other fingers come into operation to engage the grain and carry it forward, by which means the grain is forced forward continuously; and it will be seen that the fingers L', owing to the manner of pivoting and supporting them, will be forced vertically into the grain, and will be drawn from the grain in the same manner, by which means each finger will carry the grain forward of it to the extent of its travel, and then leave it directly.

What I claim as new, and desire to secure by Letters Patent, is as follows:

1. The clutch-tripping lever H, bracket I, and swinging arm I', in combination with the driving-wheel E, having a track or flange, E⁴,

and a clutch mechanism connected with the driving-pinion, substantially as and for the 30 purposes specified.

2. The clutch-tripping lever H, arm I, swinging arm I', and wheel E, having the track or flange E⁴, in combination with the clutch-dog G', driver G, and pinion F, for throwing the 35 binding apparatus into and out of gear, substantially as specified.

3. The clutch-tripping lever H, arm I, swinging arm I', wheel E, having the flange or track E⁴, and spring J, in combination with a clutch-dog, G', driver G, and pinion F, substantially 40 as and for the purposes specified.

4. The clutch-tripping lever H, swinging arm I', driving-wheel E, having flange E⁴, and a clutch mechanism, in combination with a 45 compressor-finger and a connection between the finger and the clutch-lever, substantially as and for the purposes specified.

5. The frame U', having a slot, U'', and carrying a finger, U, in combination with a crank-shaft, N', cranks n', and pitman-rod n'', substantially as and for the purposes specified.

WILLIAM F. OLIN.
